US0D1009374S

(12) **United States Design Patent** (10) **Patent No.:** **US D1,009,374 S**
(45) **Date of Patent:** **** Dec. 26, 2023**

(54) **ARTIFICIAL LASH EXTENSION**

(71) Applicant: **Lashify, Inc.**, North Hollywood, CA (US)

(72) Inventor: **Sahara Lotti**, North Hollywood, CA (US)

(73) Assignee: **Lashify, Inc.**, North Hollywood, CA (US)

(**) Term: **15 Years**

(21) Appl. No.: **29/890,075**

(22) Filed: **Apr. 19, 2023**

Related U.S. Application Data

(63) Continuation of application No. 29/768,147, filed on Jan. 27, 2021, now Pat. No. Des. 988,608.

(51) **LOC (14) Cl.** **28-04**

(57) **CLAIM**

The ornamental design for an artificial lash extension, as shown and described.

DESCRIPTION

FIG. 1 is a top left perspective view of an artificial lash extension in accordance with the claimed design, shown in an embodiment;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines consisting of evenly spaced lines in the figures show portions of the artificial lash extension that form no part of the claimed design.

1 Claim, 7 Drawing Sheets
